UNITED STATES PATENT OFFICE.

GEORGE FRANCIS TOPLIFF, OF BOSTON, MASSACHUSETTS, ASSIGNOR TO THE
UNITED STATES MAIL-BOX COMPANY, OF SAME PLACE.

DESIGN FOR A LETTER-BOX.

Specification forming part of Design No. 5,264, dated September 12, 1871.

To all whom it may concern:

Be it known that I, GEORGE FRANCIS TOPLIFF, of Boston, in the county of Suffolk and State of Massachusetts, have invented certain Improvements in Design for Mail-Boxes, of which the following is a specification:

Figure 1 in the drawing is a central vertical section, Fig. 2 is a front view, Fig. 3 is a side view, and Fig. 4 is a central horizontal section of my improved design.

The present invention relates to certain new and useful improvements in the design of mail-boxes for private use; and consists in a box, *a a a*, for receiving letters, &c., with one of its sides formed into two quarter-round curves, *b b e e*, joined at their intersection by a bead, *d*, and its bottom shaped with a curve, *e e*, formed by two arcs of a circle, and finished with a fillet, *f*, and a torus or partial bead, *g*. The top of the box *a a a* is arranged with a movable sloping lid, *h*, the edge *i* of which is rounded so as to fit over the curve *b b*. Above and back of the lid *h* the top *i* of the box *a a a* is of an ogee-shape, fin-

ished with a torus or partial bead, *l*, between two fillets, *m n*. The top of the box slopes from the bead *d* back to the fillet *m* in the shape of an ogee, *o*, and the edge *p* of the torus *l* is rounded like its front. The bottom portion of the curve *e e* slopes back from the bead *d* to the fillet *f*, which connects it with the torus *g*, the end of the latter being rounded like its face. The face of the box *a a a* is raised a little, as at *q q*, from the surface of the curves *b b e e*, and has a sunk panel, *r r*, formed on it.

Having thus fully described my improvements, what I claim as my invention, and desire to secure by Letters Patent, is—

The design for a mail-box, as herein set forth.

In testimony whereof I have signed my name to this specification in the presence of two subscribing witnesses.

GEORGE FRANCIS TOPLIFF.
